UNITED STATES PATENT OFFICE.

WILLIAM B. HAYDEN, OF COLUMBUS, OHIO.

HAME.

SPECIFICATION forming part of Letters Patent No. 257,699, dated May 9, 1882.

Application filed April 3, 1882. (Model.)

To all whom it may concern:

Be it known that I, WILLIAM B. HAYDEN, a citizen of the United States, residing at Columbus, in the county of Franklin and State of Ohio, have invented new and useful Improvements in Hames, of which the following is a specification.

This invention relates to that class of harness-hames in which each side or leg of the hames is provided with a metal top or tip and the metal loop of the upper hame-strap engaged with a rack or series of studs upon the concave side of the hame-tip and then locked in position by passing the hame-strap between the loop and the convex side of the metal top.

I am aware that a metal hame-top has been formed with a longitudinal opening crossed at regular intervals by a series of bars, around which the upper hame-strap is looped; but my improvement relates solely to that class of hame-tops in which a metal clasp or loop is adjusted upon and engaged with the hame-top and then held in its engagement with the hame-top by passing the leather strap between the latter and the metal loop.

I am also aware that a hame has been formed with two lines of reticulations in one of its sides, and also that a hame has been provided with a groove having a line of recesses in one side, into which a projection on the loop is recessed. Both these hames lack the feature of a slotted hame, having raised portions located along the walls of the slot, and provided with sockets, and the loop having two studs, which are received in the sockets, as hereinafter more fully described.

To attain the objects of my invention I form the metal hame-top with a longitudinal slot or channel, having along its opposite side walls a series of raised portions provided with seats or sockets opening at the concave side of the hame-top, and I provide the metal loop with a pair of studs projecting inwardly from one of its cross-bars, these studs being fitted in the sockets after adjusting the loop to the proper height upon the metal top, and the hame-strap may then be passed between the opposite cross-bar of the metal loop and the convex side of the hame-top, thereby preventing the studs from accidental removal from the sockets

until the strap has been withdrawn from its connection with the loop.

I will now proceed to describe my invention with the aid of the accompanying drawings, wherein—

Figure 1 is a perspective view of my improved hame-top with the metal loop engaged therewith. Fig. 2 is a longitudinal section of the extension-top and metal loop. Fig. 3 is a transverse section taken through the metal top with the loop connected therewith.

The same letters of reference indicate like parts in the several figures.

The extension metal top A is of cast metal, and formed at its lower end with legs or straps a, between which the upper end of the hame-leg B is secured by bolts, as shown. One of these bolts may be the usual eyebolt for carrying the rein-guard C.

I prefer to curve the hame-top outwardly from its lower to its upper end, as this form adds greatly to the appearance of the hames, the outer and inner sides of the top presenting respectively concave and convex surfaces a' and a''.

The top is provided with a longitudinal channel or slot, D, being formed in the hame-top. Along the walls of this slot are a series of raised portions, a³, extending from the flanges a⁴, that run along the convex side thereof. Each raised portion a³ is provided with a U-shaped socket or depression, d', the open sides of which face said concave outer edge of the hame-top, and are adapted to receive short lugs or studs e, projecting inwardly from one of the end bars of the metal-strap loop E. This metal loop E and its inwardly-projecting studs e are made of such relative length that the studs can only be disengaged from the U-shaped depressions d' when the opposite end of the link is moved close up to the convex side of the tip. It is therefore obvious that said tongues or studs e cannot be disengaged from the depressions for the purpose of adjustment while the upper hame-strap is in the link and interposed between its end bar that is opposite the bar carrying the studs and the edge of the top.

The advantages of this arrangement will be apparent to those familiar with this class of de-
